Design No. 2,769, dated August 27, 1867.

DESIGN FOR A STATUETTE.

The Schedule referred to in these Letters Patent and making part of the same.

The present invention relates to a Design for a Statuette of U. S. Grant, General of the Armies of the United States of America. This design is illustrated in the accompanying plate by a photographic view of the statuette, and consists of a pedestal, A, of suitable form and size, upon the top of which is placed the figure, in full length, of General U. S. Grant, in a position sitting on a chair covered by his cloak, B, and with his right hand, C, grasping the upper part of the right lappel of his coat, D, which is represented as unbuttoned; in his left hand, E, holding a cigar, F, and his left leg, G, resting across his right leg, H.

Claim.

The design for a statuette, substantially as described and shown.

The above specification of our invention signed by us this 6th day of July, 1867.
